UNITED STATES PATENT OFFICE.

HENRY SCOTT BREWINGTON, OF BALTIMORE, MARYLAND.

FOUNTAIN MARKING-BRUSH.

SPECIFICATION forming part of Letters Patent No. 469,990, dated March 1, 1892.

Application filed October 1, 1891. Serial No. 407,364. (No model.)

To all whom it may concern:

Be it known that I, HENRY SCOTT BREWINGTON, a citizen of the United States, residing at Baltimore, in the State of Maryland, have invented certain new and useful Improvements 5 in Fountain Marking-Brushes, of which the following is a specification.

This invention relates to an improvement in fountain marking-brushes; and the object 10 is to simplify the construction for governing the flow of fluid to the brush, at the same time rendering the same more effective and arranging for the feeding of the fluid into the center of the brush.

15 To this end the invention may be said to consist in the novel features of construction and combinations of parts hereinafter described and claimed.

The invention is illustrated in the accompanying drawings, in which—

Figure 1 represents an exterior view of the device; Fig. 2, a longitudinal section with the parts adjusted to cut off the flow of fluid to the brush; Fig. 3, a similar section with the parts adjusted to permit the fluid to flow into the brush; Fig. 4, an exterior view of the handle, and Fig. 5 a section of the cap.

The device comprises a tubular handle A, constituting the reservoir for fluid and provided at one end with a cap a and at the opposite end with an exterior screw-thread b, beyond which is a straight plain portion c and a conical end d, closed at its extremity. The outlet from the hollow handle is through 35 small lateral openings or ports e in the conical part of the end d, and in the present instance there are two of these ports on opposite sides. I provide a cap B, which has an internal thread b' to take on the external 40 thread of the tubular handle, a straight plain portion c' to correspond to the straight portion c of the handle, and beyond this straight portion a conical seat d' for the end d of the handle. The cap is tapered on its exterior 45 and terminates in a small tubular end f. The brush C is fastened on a tapering nozzle g, which screws into the said tubular end f and opens at its outer end into the middle of the brush and at its opposite end into the center 50 or base of the conical seat d'. It will be observed that this nozzle forms the stock of the

brush, and by constructing it as a separate piece from the cap B to screw into the same brushes of different kinds and sizes, but having a uniform stock or nozzle, may be fitted to 55 said cap. The cap B is screwed onto the tube A by means of the threads b b', and it will be seen that it can be turned until the conical end d of said tube fits snugly against the seat d' of the said cap, when said seat serves as 60 a valve to close the ports e and confine the fluid. Now upon turning back the cap B the seat or valve d' is moved away from the conical end d and the fluid flows through the ports e, which are thus opened, and down the 65 space formed between the said seat and the said conical end into the nozzle f, which conveys it into the center of the brush C. It will thus be observed that the threads b b' not only serve as a means of connection between 70 the cap B and handle, but also as a means for governing and regulating the feed of the fluid, for by turning the said cap more or less a greater or less amount of fluid is fed to the brush. It will be seen that by this arrangement 75 a very fine adjustment may be had, so that the desired amount of flow of the fluid may be exactly obtained. The interior plain straight portion c' of the cap B is lined with packing h of suitable material, forming a 80 bushing in which the straight plain portion c of the tubular handle A fits and is movable. The said bushing is of such a length that while the cap B is on the handle it will always 85 close the space between said cap and handle, and thus prevent the fluid from working back through such space.

Having thus described my invention, what I claim as new, and desire to secure by Letters Patent, is—

1. In a fountain-brush, the combination of 90 a tubular handle to contain the fluid, having external screw-threads at one end and a conical part beyond said threads, with lateral 95 openings or ports leading out of the interior of the tubular handle, a tubular cap screwing onto the end of the handle and having a conical seat for the conical part of the said handle, which seat serves as a valve to open and close the lateral ports or openings in the latter by the turning of the cap, and a brush on 100 the end of the cap.

2. In a fountain brush, the combination of a tubular handle to contain the fluid, having external screw-threads at one end and a conical part beyond said threads, with lateral 5 openings or ports leading out of the interior of the tubular handle, a cap screwing onto the end of the handle and having a plain straight portion to correspond to that of the handle, and a conical seat for the conical part of the handle, which seat serves as a valve to open and close the lateral 10 ports or openings in the latter by the turning of the cap, a detachable nozzle screwing into the end of the cap, and a brush secured on said nozzle.
3. In a fountain-brush, the combination of 15 a tubular handle to contain the fluid, having external screw-threads at one end, a plain straight portion beyond said threads, and a conical portion beyond said straight portion,

with lateral ports or openings leading out of the interior of the tubular handle, a tubular 20 cap screwing onto the end of the handle and having a plain straight portion to correspond to that of the handle, and a conical seat for the conical portion of the said handle, which seat serves as a valve to open and close the 25 lateral ports in the latter by the turning of the cap, a packing or bushing between the plain straight portions of the cap and handle, and a brush on the end of the cap.

In testimony whereof I affix my signature in 30 the presence of two witnesses.

HENRY SCOTT BREWINGTON.
